RANGE

Henry Moecker, Jr., William H. Frick, Edward M. Meacham, and Harold K. White, Cleveland, Ohio, assignors to American Stove Company, St. Louis, Mo., a corporation of New Jersey

Application July 3, 1940, Serial No. 343,846

16 Claims. (Cl. 126—38)

This invention is directed generally to cooking ranges or the like in which the cooking is accomplished by gas or other fluid fuel burners, but the invention pertains more particularly and specifically to what we term, and which are generally referred to, as heavy duty ranges such as are used for commercial cooking operations as performed in hotels, restaurants and other places and institutions where cooking on a large scale is performed.

The range is of the solid cooking top type, as is usually the case in heavy duty ranges, and one of the primary objects of the invention is that of providing in a range of this type adequate cooking heat on all areas of the cooking top notwithstanding the fact that the cooking top has a much greater area than and as a consequence extends a considerable distance beyond all sides of the burner which is utilized to heat said top.

Another object of the invention is to provide a construction in which the cooking top can be quickly and efficiently heated.

In the accomplishment of the objects above recited a novel top construction is provided in combination with a novel fluing arrangement for the burner chamber which lies beneath said top.

Another and further object of the invention is to provide an improved manner of supplying and distributing secondary air to the burner within the closed cooking top burner chamber and utilizing the construction which accomplishes said object to serve as a means for protecting the burner from "spill-overs" or "boil-overs" which occur on the cooking top of the range.

Other objects, novel features of construction and improved results of a range built in accord with the present invention will appear from the following description and the accompanying drawings which illustrate an embodiment which the invention may take in the provision of a range which performs to accomplish the desired results.

In the drawings:

Fig. 1 is a vertical sectional view through the cooking top of a range built in accord with the present invention.

Fig. 2 is a vertical sectional view taken at right angles to Fig. 1.

Fig. 3 is a top plan view of the range appearing in Figs. 1 and 2 of the drawings, one-half of the cooking top being removed and parts of the range top being broken away to better illustrate the construction.

Fig. 4 is a fragmentary underside perspective view of the cooking top illustrated in Figs. 1 to 3 of the drawings.

Fig. 5 is a fragmentary transverse vertical sectional view through the cooking top of a range illustrating a modified form of the invention.

Fig. 6 is a plan view of the plate above the burner and forming a part of the modified construction illustrated in Fig. 5 of the drawings.

Fig. 7 is a bottom plan view illustrating a modified form of the cooking top plate.

Fig. 8 is an enlarged detail sectional view taken on the line 8—8 of Fig. 6.

Having reference now to the drawings and particularly to Figs. 1 to 4 inclusive thereof, A designates a baking or cooking oven which is usually a conventional part of a cooking range and above the fully insulated top 1 thereof is a chamber, usually referred to generally as a burner chamber in that within this chamber is the burner or burners utilized to heat the solid cooking top upon which the open cooking operations are performed.

In the present construction the solid cooking top is made up of a plurality of pieces all of which are supported and disposed to provide a smooth horizontally disposed surface. Beginning at the front of the range there is a transversely extending top element 2 which partakes of the nature of a frame. This element is suitably supported upon the fully insulated front wall 3 of the burner chamber and at its front edge is bent downwardly to provide an apron-like portion 4 while its inner edge is bent downwardly and horizontally into the burner chamber to provide a transversely and horizontally disposed supporting flange or shoulder 5.

At its rear the cooking top is provided with a transversely extending plate 6 which partakes of the nature of a top frame in that it, like the front member 2, is utilized as a supporting means for the main solid cooking top of the range. At its inner edge the rear plate 6 is bent downwardly and inwardly to provide a horizontally disposed flange or shoulder 7 which lies in the same plane as the shoulder 5 of the frame member 2.

The frame members 2 and 6 are supported at their ends upon angle irons 8 which extend from front to back at the ends or sides of the range and which themselves are supported upon the outwardly turned upper ends 9 of the side or end walls 10 of the cooking top chamber.

Short of its rear end the range top back plate frame member 6 is provided with a transversely and upwardly extending flange 11 the front face

of which is curved as at 12 and a downwardly and transversely extending flange 13 immediately beneath said flange 11. The rear end of the plate is provided with a downwardly extending flange 14. The upper ends of the walls 15 of a flue box 16 telescope the flanges 13 and 14. The bottom of this flue box is attached as at 17 to the rear wall 18 of the range and braced by a bracket 19. A lower flue box 22 communicates with the oven A and the upper flue box 16.

A stack pipe 23 is supported on the rear end of the top plate 6 above an opening 24 provided therein. The lower ends of this stack are bent to form horizontal flanges 25 which abut suitable upwardly extending flanges 26 provided on the top plate 6. The front wall of the stack pipe closely abuts the plate flange 11 and the construction is such that "spill-overs" or "boil-overs" cannot without great difficulty enter the space between the flange and the stack pipe which assists in maintaining a cleaner range.

The main cooking top of the range is composed of a pair of identical plates which are substantially rectangular in shape and one of which is indicated at B and the other at C in Fig. 2 of the drawings. These plates between them extend entirely across the range and each is of a length to extend from the front top frame plate 2 to the rear frame plate 6. At their outer edges these main plates B and C are supported as indicated at 27 in Fig. 2 of the drawings while at their front edges they are supported upon the shoulders 5 of the plate 2 and at their rear edges upon the shoulders 7 of the rear frame plate 6.

At their inner edges the plates are provided with a semi-circular cut-out portion 28 provided with a depressed and surrounding flange or shoulder 29. The remaining and straight inner side edges of one plate are provided with a depressed and horizontally extending flange or shoulder 30 which acts as a support for the adjacent edge of the other plate, as clearly indicated at 31 in Fig. 2 of the drawings.

The opposed semi-circular cut-out portions of these plates B and C form a circular opening in which are positioned a ring plate D and a circular plate E. The ring plate D is supported as indicated at 32 in Fig. 1 of the drawings on the shoulders 29 of the semi-circular cut-out portions of the plates B and C while the plate D at its inner edge is provided with a circumferentially extending and depressed flange or shoulder 33 upon which is supported the circular plate E as indicated at 34 in Fig. 1 of the drawings. By reference to the drawings it will be seen that the front and rear frame plates 2 and 6 in combination with the main plates B and C and the supplemental ring plate D and circular plate E form a complete closure for the upper end of the burner chamber and that the tops of all the plates are in horizontal alignment to provide a smooth solid top over which a utensil may be readily slid.

The under sides of the main plates B and C are especially constructed in a manner and for a purpose which will be hereinafter particularly described.

A drum having an open top is centrally located within the cooking top burner chamber and is defined by a wall 35 the lower end of which is inturned horizontally and suitably secured as at 37 to the upper face of the chamber bottom which is formed by the baking oven top 1. A pair of concentrically arranged burners are positioned 75 wards the burner jets 41 of the outer burner

within the drum adjacent but slightly below the open upper end thereof. One of said burners is designated at F and is ring-like in form in that it has a central opening 38 while the other burner G is a second ring surrounding the first burner and in spaced relation thereto to provide a circular opening or passageway 39. The inner burner F on its upper face is provided with a plurality of upwardly extending burner jets 40 which by reference to Fig. 3 of the drawings will be seen to be arranged as shown while the outer burner G on its upper face is provided throughout the length thereof with a plurality of burner jets 41 arranged in spaced relationship and extending upwardly from the top of the main burner body.

By reference to Fig. 3 of the drawings it will be seen that the outer burner is suitably supported from the drum wall 35 by brackets 42 and that the outer burner is in spaced relationship to the drum wall to form an annular passageway 43. The inner burner is supported, as indicated at 44 in Fig. 1 of the drawings, by the outer burner. A separate and distinct gas or other fuel supply is provided for each of the burners and is obtained by carrying the fuel inlet manifold pipes 45 and 46 of the burners outwardly to a point beyond the front 3 of the burner chamber and connecting the same to a main gas supply pipe 47 which is positioned beneath the overhang of the top frame plate 2. The fuel connection for each of the burners is made by any suitable and conventional valve or cock 48 and manual manipulation of the valve handles 49 thereof permit independent or conjoint use of the burners as the need for heat upon the cooking top requires.

Primary air for the burners is provided in the usual manner through the mixing bell ends 50 of the burner inlet manifolds 45 and 46 respectively. Secondary air is admitted into the burner chamber near its bottom and exteriorly of the burner drum through a plurality of openings 51 provided in the side or end walls 10 of the chamber. Additional secondary air is admitted into the rear end of the chamber adjacent its bottom through openings 52 provided in the rear wall of the burner chamber which is formed by the upwardly extending end 53 of the baking oven rear wall 18 and through the enlarged openings 54 through which the burner mixing tubes 45 extend.

The secondary air which enters the openings 51, 52 and 54 is admitted into the lower end of the burner drum through four openings 55 provided in spaced relationship around the bottom of the burner drum. The secondary air once it has entered the bottom burner drum is then efficiently delivered to the burner ports or jets of the burners by what we have termed combination aeration plates and "spill-over" trays designated at H and K. These members are in the form of rings each of which has a specific cross sectional configuration. The outer ring or member 65 H is disposed within the annular space or passageway 43 between the burner drum wall and the outer ring burner G and is of substantially a U-shape in cross sectional configuration. The upper end of the outer wall of this member is bent to form a channelway to receive the upper end of the burner drum wall and in this manner have supporting relationship with the drum as indicated at 56 in Fig. 1 of the drawings. The inner wall 57 of the member flares inwardly towards the burner jets 41 of the outer burner

ring to provide an annular passageway through which secondary air is efficiently delivered to the base of the flames at said burnet jets.

The inner aeration plate and "spill-over" tray K is substantially V-shaped in cross sectional configuration and is disposed in the annular base or passageway 39 between the inner and outer burner rings. The side walls making up this member are flared toward the burner jets carried by the adjacent burner rings but the member is so disposed as to form at each of its sides an annular secondary air passageway. Secondary air in its travel through the passageway at each side of this member is directed or distributed to the bases of the burner jets of the two burners.

Due to the flare of the inner wall of the outer member H and the flare of both walls of the inner member K these members tend to protect the burner jets or ports from any spill-overs or boilovers on the cooking top which might leak or run through the joints between the cooking top plate members B, F and D. By reference to Fig. 1 of the drawings it will be seen that these trays H and K are positioned beneath the meeting edges of said cooking top plates and that their contour is such as to catch and retain any foreign matter which passes downwardly through the cooking top. This construction not only protects the burner jets but is of material assistance in maintaining a sanitary range.

The inner tray K is supported upon the inner burner ring by a plurality of wings 58 which appear in Fig. 1 of the drawings.

From the construction thus far described it will be seen that the burners are within a drum the upper end of which is partially closed by the combination plates and spill-over trays H and K the construction and arrangement of which is such as to feed or distribute secondary air to the burner ports in a highly efficient manner.

The chamber which lies between the top 1 of the cooking oven and the solid cooking top has been referred to as the cooking top burner chamber and that portion of this chamber which lies about and surrounds the burner drum is divided into upper and lower chambers by a horizontally disposed plate 59 the side edges of which, see Fig. 2 of the drawings, are bent upwardly and suitably secured as at 60 to the metallic plates 61 which are in spaced relationship to the side walls 10 of the range and act as carriers or housings for suitable insulating material 62. The lower horizontally disposed ends 63 of the plates 61 are free to give which provides for the division plate 59 a support which will permit some degree of lateral expansion and contraction of the division plate brought about by the heat to which it is subjected. At its front end the plate is secured to the front wall 3 as at 64 while at its rear end the plate is provided with a support providing for expansion and contraction in a considerable degree. By reference to Fig. 1 of the drawings it will be seen that the upper end 53 of the rear wall 18 is provided with a transversely extending bracket-like member 65 which is arranged in spaced relationship to the wall 53 and that the rear end of the plate 59 is turned downwardly as at 66 into the space between the bracket and the wall 53. This loose fitting support will permit lateral contraction and expansion of the division plate 59. As a further support for the division plate we provide a vertically disposed plate 67 which is perforated so as to form no obstruction to the passage of secondary air 75

which is admitted through the openings 52 at the rear of the burner chamber. It will be obvious that the plate 59 is provided with an opening 68 for the passage of the burner drum 35. It will also be understood that from the construction thus far described the division plate 59 provides the burner chamber in a manner to make the combustion chamber portion thereof lie entirely above the plate 59 with the result that the products of combustion generated by the burners cannot flow downwardly or strike back to intermix with the secondary air being fed to the burners. This is a desirable feature as will be understood by those skilled in this art.

The extension 53 of the cooking oven rear wall 18 constitutes the rear wall for the burner chamber including the combustion chamber portion thereof but the upper-most end 69 of this wall stops short of the under side of the rear cooking top frame plate 6 so that there is a passageway 70 providing communication between the rear end of the combustion chamber and the cooking top flue box 71 which is in direct communication with the main outlet stack 23 which extends completely across the rear end of the range. The oven gases are thus vented into the stack at a point above the cooking top.

In addition to acting as a burner chamber division plate the plate 59 serves as a support 30 for the refractory slabs M. These slabs completely cover the plate 59 and underlie all of that portion of the solid cooking top which covers that portion of the combustion chamber which surrounds the burner drum. Immediately adjacent the burner drum these refractory slabs have a substantially thick portion 73 while at their outer edges the slabs are reduced in thickness as at 74 to provide side flues or flue passageways or conduits 75. At their front edges the slabs are similarly reduced in thickness to provide a transversely extending flue conduit or passageway 76 the ends of which are in communication with the front ends of the side conduits 75. At their rear ends the slabs are also reduced in thickness to provide a combustion chamber 40 having a greater depth, as is indicated at 77 in Fig. 1 of the drawings. Preferably four refractory slabs are used as this facilitates their manufacture as well as their insertion into the range structure. The slabs are of a size so that at their sides they are spaced slightly away from the side of the combustion chamber, as indicated at 78 and they are also slightly spaced apart at their adjacent edges as indicated at 79 in Fig. 2 of the drawings. The upper adjacent edges of the slabs are tapered as at 80. This taper provides what we term a V-shaped groove which extends from the burner drum at opposite sides thereof outwardly to the thin portions of the slabs at the front and rear thereof.

Each of the slabs is further provided in their upper faces with a plurality of spaced and radially extending V-shaped grooves 81. These grooves have their inner ends terminating at those edges 65 of the slabs adjacent the burner drum while their outer ends extend to those portions of the slab which are of reduced thickness so that the outer ends of these grooves terminate at the surrounding flue passageways at the sides, front and rear of the combustion chamber.

Description will now be given of the under side of the main cooking top plates B and C and as these plates are of identical construction description of one of them will suffice to describe the other and to a better understanding of their

construction reference should be had to Fig. 4 of the drawings which supplement the construction as it appears in Figs. 1 to 3 of the drawings.

At their under sides these plates are provided with a plurality of spaced downwardly extending ribs or fins which extend radially from their arc or semi-circular edge 28 to their front, rear and side edges respectively. For the most part these fins are shallow, that is to say, they do not extend downwardly far enough to engage the upper face of the refractory slabs. There are two types of shallow ribs indicated on Fig. 4 as R and S respectively. The fins R extend over the inner wall making up the shoulder 29 to the outer thickened portions 82 constituting the front, rear and side edges of the plate. For a portion of their length adjacent their outer ends these fins are of reduced thickness as indicated at 83. The fins S are disposed between the fins R and have the same thickness or depth as the reduced ends 83 of the fins R and their lengths are similar to the lengths of the reduced ends 83 of the fins R with the result that although their outer ends reach and merge with the side edges 82 of the plate B their inner edges stop far short of the inner ends of the fins R.

In spaced relation we provide much deeper fins T. These fins extend all the way from the inner marginal edge of the shoulders 29 of the semi-circular portion of the plate B to the outer edges 82 thereof. These fins have a very deep portion 84 which is of a length identical to the length of the V-shaped grooves 81 in the upper faces of the refractory slabs M. This extremely deep portion of the fins merges into a thinner outer end portion 85 having a depth substantially the same as that of the outer ends 83 of fins R.

By reference to Figs. 1 and 2 of the drawings it will be seen that there is a fin T for each of the V-shaped grooves in the slabs including the V-shaped grooves formed by the tapered adjacent edges 80 of the slabs and that the fins extend downwardly into these grooves but in separated relationship to the side walls and bottoms thereof.

This non-contacting relationship between the fins T and the grooves 81 of the slabs is of material importance. In the first place it permits of variation in the manufacture of the parts making up the range which reduces the manufacturing costs over what they would be if the parts had to fit with exact accuracy. Additionally if there were a tight fit between the grooves and the fins and if the fins were of a length to touch the bottom of the grooves there would be grave possibility of damaging the refractory slabs when the cooking top plates B and C are dropped into place after they have been removed or during the assembly of the range. Most important however is the fact that the loose fitting of these parts allows for warping or distortion which might occur to some degree in the refractory slab supporting plate 59 or in the top plates B and C themselves. If the fins T were designed to touch the bottom of the grooves and warping or distortion did occur then this contact between the fins and the grooves would lift or hold the cooking top plates upward out of horizontal alignment with the rest of the cooking top of the range.

By reference to Fig. 1 of the drawings it will be seen that we have provided a pilot light burner 87 to provide for ignition of the cooking top burners F and G. This pilot light burner is

positioned between the two burners and is of a construction to burn a flame outwardly at each of its sides toward the burner jets of the adjacent main burners. A manual fuel control valve for the pilot light could be positioned at the front of the range adjacent the main burner valve handles 49 and the pilot light can be ignited by removing the center cooking top plate E. However if desired the pilot light can be of the constant burning type so that it will always stand ready to automatically ignite either or both of the main burners when fuel is permitted to flow to them by manipulation of their fuel control handles 49.

The pilot light is protected against the possibility of clogging from spill-overs or boil-overs by being disposed beneath the combined spill-over and aeration plate or ring K which is flared upwardly as at 88 immediately above the pilot light.

From the description thus far given it will be seen that the deep cooking top plate fins T in combination with the grooved refractory slabs provide in the combustion chamber a plurality of radially extending conducting passageways or channels for the hot products of combustion which extend from the burners outwardly towards the sides, front and rear of the range. At their outer ends these radially extending channels communicate either with the transverse flue passageway 76 at the front of the range, the side flue passageways 75 at either side of the range, or the space 77 adjacent the rear of the range. In each of these radially extending channels are disposed a plurality of the cooking top plate fins R and S which act as heat absorption members.

The operation of the range is extremely simple. The pilot light will ignite either or both of the main burners and as soon as ignition thereof takes place secondary air is drawn into the bottom of the cooking top burner chamber through the openings 51, 52 and 54 at the sides, front and rear of said chamber respectively. This air then passes into the bottom of the burner drum through the openings 55 and traveling upwardly therethrough is by the combined air directing and spill-over trays or plates H and K evenly distributed to the bases of the burner ports or burner jets to assure maintenance of efficient combustion. The products of combustion generated by the burners travel away from the center burner area through the radially extending passageways defined by the fins T and vent into the surrounding flue conduits 75, 76 and 77 through which they travel to eventually discharge into the cooking top flue box 71 and from it into the stack 23 from which they are carried to any convenient point of discharge.

If desired provision can be made for the stack pipe 23 to pass through a warming oven formed as a part of a high splash back at the rear of the range.

This construction assures uniform heating of the solid cooking top even at those points which are most remote from the burners and by positioning the supplemental flue box 71 under the rear cooking top frame plate 6 additional heated cooking top area is provided.

A modified form of construction of the under sides of the main cooking top plates B and C is illustrated in Fig. 7 of the drawings. The plate in this instance is designated as an entirety at W and its main difference over the previously described plates resides in the provision of obstruc-

tions to the travel of the products of combustion through the radially extending passageways between the deep fins. This plate has the same semicircular cut-out portion defined by the edge 28 and the same supporting shoulder 29 and likewise at its periphery is provided with the thickened side edges 82. There are the same short shallow fins S but the fins which correspond to the previously described fins R are designated at X and have transversely extending fins 89 arranged in spaced relation through their lengths. The deep fins corresponding to the previously described fins T are designated at Y and they also have in spaced relation through their lengths transversely extending fins 90.

The fins 89 and 90 are so disposed within each of the radially extending passageways as to render them tortuous because these cross fins tend to retard the travel of the hot products of combustion thereby assuring the maximum absorption by the stove top of the heat contained in these combustion gases.

In Figs. 5 and 6 a still further modification of the invention is illustrated, but inasmuch as this construction is identical to the hereinbefore described preferred form of the invention with the exception of the elimination of the combined ring-like air directing and spill-over trays H and K and the substitution of a differently constructed member therefor illustration of the central burner area only of the range is necessary to an understanding of this modified construction.

Those parts which are similar to the previously described parts are marked with similar reference numerals and it will be seen that there is the same burner drum 35 and that the burner chamber is divided into upper and lower chambers by the same horizontally disposed division wall or plate 59 and that the same grooved refractory slabs M are supported upon said division plate. The burners F and G are the same and although the solid cooking top is not illustrated it will be constructed as illustrated in Fig. 1 of the drawings so that the radial fins T will cooperate with the radial grooves 81 of the refractory slabs.

The combined air directing and spill-over trays or rings H and K have been eliminated and in place thereof we have substituted a substantially flat circular spill-over plate Z which is of a diameter slightly greater than that of the burner drum 35 and is supported upon the upper ends of the side walls of said drum. The plate is provided with a downwardly extending circumferential flange 92 which is inset from the peripheral edge of the plate and telescopes the upper end of the burner drum 35.

The plate is provided with a plurality of circumferential openings 93 which when the plate is properly positioned are above the burner orifices or jets 41 of the burners.

By reference to Fig. 5 of the drawings it will be seen that the burner jets or orifices are raised and extend vertically above the upper faces of the burners and are in spaced relationship to one another. The plate at its under side at a plurality of points is provided with downwardly extending lugs 94. These lugs have opposed semi-circular faces 95 which are arranged at opposite sides of the wedge shaped lower ends 96 of the lugs which lug ends enter the space between a pair of burner orifices or jets 41. These lugs will properly align the openings 93 with the burner jets 41.

The plate in addition to being provided with

the flame openings 93 is provided with three elongated slots 97, 98 and 99. The slot 97 at its outer end includes three flame openings 93 and terminates at its inner end in an enlarged circular opening 100. Intermediate its length the slot also is in communication with a second pair of flame openings 93. The slots 98 and 99 at their outer ends and intermediate their lengths are in communication with a plate burner opening 93. Both of these slots also terminate in the central plate opening 100.

In that form of the invention illustrated in Fig. 5 the burners are automatically ignited from the pilot light 87 in a manner heretofore described in respect to the first form of the invention as illustrated in Figs. 1 to 3 inclusive of the drawings.

Respecting the modified construction wherein the plate Z is utilized it will be obvious that this plate will act as an aeration plate in that the secondary air admitted to the lower end of the burner drum will pass the burner orifices as this air travels upwardly to pass through the plate openings 93 and that the plate will also protect the burners from any spill-over material which passes through the cooking top. Additionally this plate acts as a closure for the upper end of the burner drum to prevent the products of combustion above the plate from striking or traveling back to intermingle and thus contaminate the secondary air which is being fed to the burners.

Specific changes in the construction illustrated and described can be made without departing from the spirit of the invention which is to be limited only by the scope of the hereinafter appended claims.

We claim:

1. In a range, walls defining a chamber and a solid cooking top thereabove, a burner within said chamber, refractory material surrounding said burner and paralleling the under side of said cooking top but in spaced relation thereto, said refractory material being provided with grooves extending radially outwardly from said burner, said refractory material at the sides, front and rear of said chamber provided with a portion of reduced thickness which constitutes the bottom of flues positioned at the sides, front and rear of said chamber, fins carried by the under side of said cooking top and disposed in said radially extending grooves but having no contact with the side or bottom walls of said grooves, said fins in combination with said grooves forming a plurality of radially extending flues the inner ends of which are in communication with said chamber adjacent the burner and the outer ends of which are in communication with said side front and rear flues, said side, front and rear flues being also in communication with one another, and said rear flue communicating with the atmosphere exterior to the range chamber.

2. In a range, walls defining a chamber and a solid cooking top thereabove closing said chamber, a substantially centrally disposed vertically extending drum in said chamber having an open upper end terminating short of the under side of said solid top, a burner provided with a plurality of burner orifices disposed within said drum, horizontally disposed refractory material surrounding said drum and dividing said chamber exterior to said drum into upper and lower chamber compartments, said refractory material provided with a portion of reduced thickness which constitutes the bottom of flues positioned at the sides, front and rear of said upper com-

partment, said flue surrounding said burner drum and being in spaced relationship thereto, said refractory material being provided with a plurality of grooves extending radially outwardly from said burner drum, the under side of said solid top being provided with downwardly extending fins fitting loosely within said grooves and providing a plurality of radially extending flues extending from said burner to said surrounding flues, and the surrounding flue at one side of said chamber discharging to the atmosphere exterior to the chamber, whereby said cooking top is uniformly heated throughout its area by a centrally located burner.

3. A construction as in claim 1, wherein a secondary series of fins is provided at the under side of the cooking top and are disposed intermediate said first named fins, said second series of fins stopping short of contact with said refractory material and serving to act as heat absorption members to aid in the even distribution of heat to the solid cooking top.

4. A construction as in claim 1, wherein means is provided in said radially extending flues to retard the speed of travel of the products of combustion therethrough.

5. A construction as in claim 2, wherein a cover plate is loosely and removably supported on the upper end of said burner drum above said burner and is provided with a plurality of openings adapted to coincide and be aligned with the burner orifices of said burner, and means at the under side of said plate and having engagement with said burner for automatically so aligning the openings of said plate with the burner orifices of the burner.

6. In a range, front, side and rear walls defining a chamber, a solid cooking top closure thereabove, said top at its under side being provided with downwardly extending fins, a burner having a plurality of burner orifices substantially centrally located in said chamber, a drum surrounding said burner and having an open upper end, refractory material surrounding said drum and dividing the chamber exterior of the drum into an upper combustion chamber and a lower secondary air receiving chamber, said secondary air receiving chamber provided with air inlet openings, said drum being provided with secondary air inlet openings communicating with said secondary air receiving chamber, said refractory material being provided with a plurality of grooves extending radially outwardly from said drum and terminating short of the peripheral edges of said material and the side, front and rear walls of said chamber, said cooking top plate fins loosely fitting within said grooves and being of substantially the same length as said grooves, a flue beyond the outer ends of said fins and surrounding said drum and completely encircling said combustion chamber, said surrounding flue provided with an outlet opening to atmosphere, and said fins providing a plurality of radially extending flues communicating at their inner ends with said drum and at their outer ends with said surrounding flue.

7. A construction as in claim 6, wherein said fins loosely fit within said grooves, and said refractory material is yieldably supported, for the purpose described.

8. In a range, a burner having a plurality of upwardly extending spaced members each being provided with a burner port in its upper face, a drum surrounding said burner, an aeration plate loosely supported for limited horizontal

movement upon and closing the upper end of said drum, said plate being provided with a plurality of openings one each of which is adapted to be aligned with a burner port of said burner to provide a passageway for the flames from said burner ports, and elements extending downwardly from the under side of said plate, each of said elements adapted to snugly enter the space between a pair of said upwardly extending members and to engage the opposed sides of said spaced members to thereby properly position said plate with the openings thereof in alignment with said burner ports.

9. In a range, side walls and a bottom defining a chamber having an open upper end, a solid cooking top closing the upper end of said chamber, a burner within said chamber, a horizontally disposed secondary bottom within said chamber surrounding said burner and paralleling the under side of said cooking top and positioned intermediate said cooking top and said chamber bottom, said secondary bottom having a thickened portion provided with grooves extending radially outward from said burner, said secondary bottom beyond the outer ends of said grooves being of reduced thickness to provide a flue surrounding the burner and lying between itself and the under side of said cooking top, fins carried by the under side of said cooking top and disposed within said radially extending grooves but having no contact with the sides or bottom walls of said grooves, said fins constituting the side walls of a plurality of radially extending open ended flues the inner ends of which are adjacent said burner and the outer ends of which are in communication with said surrounding flue, and said surrounding flue having communication with the atmosphere exterior of said range chamber.

10. A construction as in claim 6 wherein, a closure plate provided with a plurality of openings to permit the passage of the burner flames is disposed upon the upper end of the burner drum, and said plate openings being so associated with the burner orifices of the burner as to cause all the secondary air for the burner to be drawn past said burner orifices as air passes upwardly from the lower end of the drum into the combustion chamber above the burner.

11. A burner arrangement for a range or the like comprising, a gas burner having a combination fuel and air inlet through which a mixture of gas and primary air is transmitted, a housing completely enclosing said burner and provided at a point below said burner with a secondary air inlet, said burner having on its upper face a plurality of separate and spaced vertical extensions constituting burner ports, said chamber having a cover provided with a plurality of openings one each of which is for the passage of a flame at one of said burner ports, said chamber cover being loosely supported to permit its movement in a horizontal plane, the under side of said cover being provided with a plurality of downwardly extending members each of which is of a size to span the distance between a pair of extensions constituting a pair of burner ports, and said cover extension members acting to properly position said cover with the openings thereof in vertical alignment with the burner ports of said burner.

12. A burner arrangement for a range or the like comprising, a gas burner having a combination fuel and air inlet through which a mixture of gas and primary air is transmitted, a housing

completely enclosing said burner and provided at a point below said burner with a secondary air inlet, said burner having on its upper face a plurality of separate and spaced vertical extensions constituting burner ports, said chamber having a cover provided with a plurality of openings one each of which is for the passage of a flame at one of said burner ports, said chamber cover being loosely supported to permit its movement in a horizontal plane, the under side of said cover being provided with a plurality of downwardly extending members each of which is of a size to span the distance between a pair of extensions constituting a pair of burner ports, and said cover extension members at their lower ends being of a shape to snugly engage and abut the opposing side walls of a pair of said burner extensions and acting to properly position said cover with the openings thereof in vertical alignment with the burner ports of said burner.

13. In a range, a burner having on its upper face a plurality of upwardly extending nibs having burner ports in their upper faces, a drum surrounding said burner and provided with a secondary air inlet opening disposed at a point beneath said burner, a combination aeration and burner protecting plate loosely supported upon the upper end of said drum to permit its movement in a horizontal plane, said plate closing the upper end of said drum, said plate being provided with a plurality of openings one each of which is adapted to be aligned with one of said burner ports to provide a passageway for the flames at said ports, a plurality of members carried by and extending downwardly from the under side of said plate, said members being shaped to enter the space between the side walls

of a pair of said burner nibs and acting to position and hold said loosely supported plate with the openings thereof in vertical alignment with said burner ports.

5 14. A construction such as defined in claim 13 wherein, said burner nibs are of a circular shape in cross section and said downwardly extending members at the under side of said plate have at their lower ends arc shaped cut-out portions 10 which snugly engage and abut the opposed side walls of a pair of said burner nibs.

15 15. A construction such as defined in claim 13 wherein, said burner nibs have upwardly and inwardly extending side walls and are of a circular shape in cross section, and the lower ends 20 of said plate downwardly extending members have their lower ends tapered and provided with arc shaped cut-out portions whereby said lower ends completely fill the space between a pair of said burner nibs and snugly engage and abut the opposed side walls of a pair of said nibs.

25 16. For use in a gas heating or cooking apparatus, a gaseous fuel burner provided on its upper surface with vertical extensions having therein fuel orifices, a plate supported above and extending completely over said burner, said plate provided with a plurality of openings, and means carried at the under side of said plate and engaging said burner port extensions for positioning and holding said plate so that one of its 30 openings is in vertical alignment with each of said burner ports.
